UNITED STATES PATENT OFFICE.

HERBERT N. KILBY, OF CLEVELAND, OHIO.

CARBONATING APPARATUS AND METHOD.

Application filed August 18, 1924. Serial No. 732,644.

The present invention is directed to improvements in carbonating apparatus, and particularly to one designed for the continuous carbonation of alkaline sugar juice.

As is well known in the carbonation of sugar juice the juice is thoroughly mixed with lime and afterwards subjected to the action of carbonic acid gas, which causes the impurities held in solution in the juice to settle in the apparatus, thereby producing a juice which is clear. The gas coming from the commercial kilns now used in sugar and soda ash plants never reaches a purity exceeding 40% carbonic acid gas and ranges from 20% to 40%, depending upon the type of kiln and the amount of fuel used to the amount of limestone to be burnt.

The remainder of the gas is commonly termed waste gas as it does not combine with the limed juices and serves no active part in the usual carbonating process. The character of the commercial gas from any particular kiln varies from time to time in its content of carbonic acid and waste gas, due to several causes, among which are: excesses of air entering a kiln during the time the charging door of the kiln is opened when being charged; changes in pump suction which causes the draft in the kiln to vary; also, differential in the water level in the gas washer, all of these tend to increase or decrease the amount of air entering the kiln and cause the carbonic acid gas content in the commercial gas to fluctuate. Hence it is an object of this invention to be able to control automatically these changes in the gas with the apparatus and method herein described by the utilization of the waste gases coming from the kiln gas which enters the apparatus.

A further object of this invention is to provide an apparatus of this character which is composed of a few parts so arranged that the carbonation of sugar juice will be effectively and rapidly performed.

A still further object of this invention is to provide an apparatus of this character constructed in such manner that the carbonic acid gas and juice will flow constantly during the carbonation of the juice, and the gas will be intimately commingled with the juice during the carbonation process, shortening the time the impurities, that are freed out of the juice by the action of the carbonic

gas, are held in contact with the carbonated juice.

With these and other objects in view as will appear as the description proceeds, the invention consists in the novel features of construction, combinations of elements and arrangements of parts hereinafter to be fully described and claimed.

In the accompanying drawing:

Figure 1 is a side elevation of the complete apparatus, parts being broken away and parts shown in section to disclose details of construction, and

Figure 2 is an enlarged detail view of the valve structure.

Referring to the specific embodiment of this invention illustrated in the accompanying drawing, numerals 1 and 2 designate similar carbonating vessels or tubes which are supported partially above and partially below the floor 3 by brackets 4. The lower ends of the tubes 1 and 2 are tapered and are provided with normally closed outlets 5 through which deposits of heavy material may be drawn off.

Each of the tubes is provided with a perforated partition plate 6 adjacent the bottom thereof, which serves to break up the gas and thoroughly commingle the gas and juice. The juice which is admitted below the partition plate 6 of the tube 1 by means of a valve 7 rises to the level of the juice outlet port 8 and passes down into the lower portion of the second tube. From the second tube the juice passes through the pipe line 9 into the bottom of the overflow box 10 and then to the filter press pumps (not shown).

Commercial carbonic acid gas enters through the main gas valve 11 into a T connection 12 and passes from the T connection to the chamber 13 of the regulating valve 14, hereinafter to be described, and through the valve 15 to the lower portion of the first tube 2. Each tube is further provided with a valve 16 controlling the passage of waste gas from the tubes to the roof.

A pipe line 17 connected to the upper portion of the tube 1 enters the chamber 18 above the diaphragm 19 of the valve 14 to cause the diaphragm to be subjected to the pressure of the waste gas.

To the center of the diaphragm is connected a valve stem 20 which is normally

held in its uppermost position by the expansion spring 21 having its opposite ends in engagement with the adjustable support 22 and the plate 23 on the lower side of the 5 diaphragm 19. The disk 24 is mounted on the valve stem 20 just below the chamber 13 and partially closes the conical opening 25 in the bottom of said chamber. The diameter of the disk 24 is less than the smallest 10 diameter of the opening 25 in order that the valve 14 may be partly open at all times. The lower end of the valve 14 is connected by a pipe line 26 to the lower portion of the second tube. It is to be noted that extensions 27 are provided from all the valves 15 so that they may be conveniently operated from the floor 3.

The pointer 28 rigidly secured to the valve stem 20 travels over the scale 29 to indicate 20 the quality of the gas entering the apparatus at all times and a small faucet 30 is attached to the overflow box so that samples of the juice may be obtained.

The operation of the apparatus is as follows:

The sugar juice is normally kept in large tanks (not shown) located at a level above that of the carbonating apparatus and is mixed with the proper amount of lime 30 oxide before entering the apparatus. Upon opening of the valve 7 the limed juice passes into the first tube at an approximate pressure of three and one-half (3½) pounds and the pressure of the gas is at all times maintained constant and equal to the juice pressure, both of these pressures being regulated exteriorly of the apparatus.

The juice valve 7 is first opened about half and the alkalinity is fixed to the desired 40 amount, after which the main gas valve 11 is opened and the alkalinity regulated by the valve 15. This valve 15 is never touched after the apparatus is set in operation, but the waste gas valve 16 connected with the 45 vessel is now partially closed and a pressure created in this vessel, which pressure acts on the diaphragm 19 to force the disk 24 to take the position at the large end of the conical opening 25, when the commercial 50 gas employed runs 20% in carbonic acid content, and into the center of the opening if the gas contains 30% carbonic acid gas. It is obvious that the pressure of the waste 55 gas will be greater with the same opening of the valve 16 as the carbonic acid content of the gas used decreases.

Next, to correct the change in alkalinity caused by more gas going into the second tube, due to the increase in area around the 60 disk 24, the juice valve 7 which was partly open is further opened to bring the alkalinity of the juice back to the original state. The valve 15 permits the same quantity of gas to enter regardless of the percentage of 65 carbonic acid in the gas.

As the commercial gas increases in content of carbonic acid the waste gas coming from it decreases and hence the volume leaving the waste valve will be less, causing the pressure of the waste gas to decrease, thus reducing the pressure on the diaphragm 19. The disk 24 due to this decrease in pressure rises cutting down the amount of gas going into the second tube, and thereby restores the original alkalinity.

The valve disk 24 and the opening 25 are designed for gas ranging from 20% to 40% in carbonic acid content which is the usual range of the gas delivered by the kilns now in use.

It is to be noted that in an apparatus of this character by carbonating the juices under pressure the absorption of carbonic acid gas is more quickly accomplished and any irregularities in the character of the supply 85 of commercial gas is taken care of without injury to the juice under treatment. As the carbonic acid content of the commercial gas employed increases and decreases, the apparatus automatically decreases and increases 90 the total amount of gas entering the apparatus, thereby insuring a uniform quantity of carbonic acid gas for action upon the sugar juice.

What is claimed is:

1. In carbonating apparatus, separate communicating vessels, means for introducing alkaline sugar juice under a substantially constant pressure into said vessels, means for introducing a partially absorptive gas under a pressure substantially equal to that of said juice into said vessels, said gas having a variable carbonic acid content, and means operable automatically by variation in the pressure of the unabsorbed gas content remaining in one of said vessels to vary the volumetric inflow of the carbonic acid gas into the other of said vessels.

2. In carbonating apparatus, a carbonator including a pair of separate chambers, means connecting said chambers to maintain a uniform liquid level therein, means for causing a constant circulation under substantially uniform pressure of limed sugar juice through said chambers, means for introducing a partially absorptive gas under a substantially constant pressure into said chambers for intermingling with said limed juice, and means operable automatically by variation in the pressure of the unabsorbed gas remaining in one of said chambers to vary the inflow of said absorptive gas into the other of said chambers so as to subject said juice to a predetermined quantity of said absorptive gas irrespective of fluctuations in the carbonic acid content of said gas.

3. An apparatus of the class described comprising a plurality of carbonating vessels, means for conducting alkaline sugar juice and partially absorptive gas at substan-

tially uniform pressures simultaneously into said vessels and means for utilizing the unabsorbed portion of the gas in one of said vessels to control the flow of partially absorptive gas into the other vessel.

4. An apparatus of the class described comprising a plurality of carbonating vessels, means for conducting alkaline sugar juice to the vessels, means constantly per-

mitting partially absorptive gas at a pressure substantially equal to that of the juice to flow into the vessels and means controlled by the unabsorbed gases in one of said vessels to regulate the flow of gas into the other vessel.

5. An apparatus of the class described comprising a plurality of carbonating vessels, means permitting the continuous flow of alkaline sugar juice through said vessels, means for commingling partially absorptive

gas with the juice in the vessels and while said juice and gas are maintained at substantially uniform pressures, and means for automatically controlling the flow of gas into one of said vessels by the pressure of the unabsorbed portion of the gas in the other vessel.

6. An apparatus of the class described comprising a plurality of carbonating vessels, means permitting of a continuous flow of alkaline sugar juice through said vessels

30 at a substantially uniform pressure, means for commingling partially absorptive gas with the juice in the vessels while said gas is maintained at a pressure substantially equal to that of said juice, means restricting the

35 passage of the unabsorbed portion of the gas from the vessels so as to cause a pressure in the vessels and means for automatically controlling the flow of gas into one of the vessels by the pressure exerted by the unabsorbed gases coming from the gas that enters the other vessel.

7. An apparatus of the class described comprising a carbonating vessel, means for introducing limed sugar juice therein at a substantially uniform pressure, means for subjecting the juice to the action of a partially absorptive gas at a pressure substantially equal to that of the juice pressure, and means whereby the juice is subjected to the action of a substantially constant quantity of absorptive gas as the absorptive content of the partially absorptive gas varies in volume.

8. An apparatus of the class described comprising a plurality of carbonating vessels, means permitting the commingling of alkaline sugar juice with commercial carbonic acid gas therein and wherein the pressure of the gas is maintained substantially constant and equal to that of the juice pressure, and means for varying the quantity of gas entering the apparatus as the gas varies in carbonic acid content.

9. In carbonating apparatus, a pair of vessels arranged in inter-communicating rela-

tion, means for circulating alkaline sugar juice under a substantially constant pressure through said vessels, means for introducing a gas having a carbonic acid content under a substantially constant pressure in the said vessels for commingling with said juice, a restricted outlet provided in one of said vessels operating to permit of the creation of a gas pressure in said latter vessel by the accumulation of unabsorbed gas therein, and an automatically operating valve responsive to the variation in the gas pressure created within said last named vessel to vary the inflow of carbonic acid containing gas into the other of said vessels.

10. In apparatus of the class described, a carbonating vessel, means for introducing under relatively constant pressures a carbonic acid containing gas and alkaline sugar juice simultaneously into the vessel, an auxiliary gas inlet, and an automatically operated valve mechanism responsive to varying gas pressures created in said vessel by the accumulation of unabsorbed gases for controlling automatically the volumetric flow of gas through said auxiliary inlet.

11. In apparatus of the class described, a carbonating vessel, an inlet for introducing alkaline sugar juice and a partially absorptive gas under substantially equal pressures simultaneously into said vessel, and means for utilizing the unabsorbed portion of said gas to control the flow of the partially absorptive gas into the vessel.

12. In apparatus of the class described, a carbonating vessel, means for circulating alkaline sugar juice and a partially absorptive gas under substantially equal pressures through said vessel, and means governed by the accumulation of unabsorbed gases within said vessel to regulate automatically further flow of the partially absorptive gas to the vessel.

13. In apparatus of the class described, a carbonating vessel and tank in communication with said vessel, means for simultaneously conducting a gas having an absorptive carbonic acid content and alkaline sugar juice under substantially equal pressures to the tank, an auxiliary source of carbonic acid gas supply for the vessel, and an automatically operated valve means responsive to variations in pressure of the unabsorptive gas released from the juice in said tank to regulate the flow of gas through said auxiliary source of supply.

14. In apparatus of the class described, a carbonating vessel, means for conducting alkaline sugar juice and a partially absorptive gas under substantially uniform pressures simultaneously into said vessel, and means for utilizing the unabsorbed gases released from the juices in the vessel to control the further flow of partially absorptive gas into engagement with said juice so as to main-

tain a constant amount of lime oxide in the carbonated juice discharged from the apparatus.

15. In apparatus of the class described, a carbonating vessel, an auxiliary carbonating vessel adjacent thereto, means for conducting an alkaline juice and carbonic acid gas under substantially uniform pressures into both vessels, means for controlling the flow of carbonic acid gas into the first vessel, and valve means for controlling automatically the carbonic acid gas entering the auxiliary vessel, said valve means being responsive to the fluctuating pressures of unabsorbed gases stored in said vessel.

16. The method of carbonating alkaline sugar juices, which consists in simultane-

ously introducing alkaline sugar juice and a partially absorptive gas having a variable carbonic acid content under substantially uniform pressures into a receiving vessel, and in utilizing the variable pressures of the unabsorbed portions of said gas issuing from said juice to increase or diminish the further volumetric inflow of said carbonic acid gas into engagement with the juice, whereby the effective quantity of carbon-dioxide introduced into said juice is maintained constant irrespective of the fluctuating proportions thereof existing in the gas in its original form.

In testimony whereof I affix my signature.

HERBERT N. KILBY.
